ICE TRAY

Clifford R. Carney, Miami, Fla.

Application October 28, 1938, Serial No. 237,453

8 Claims. (Cl. 62—108.5)

This invention relates to an ice tray of the type provided with a removable grid, and more particularly to a grid for such trays which is easily and quickly removable from the tray and which is provided with manually actuated mechanical means for releasing the ice cubes formed therein.

It is an important object of the present invention to provide an ice tray grid which is so constructed as to permit the mechanical removal not only of the grid from the tray but also of the ice cubes from the grid by a continuous application of power to the grid.

Another object of the invention is to provide an ice tray grid which is so constructed as to effect the progressive release of either all or a portion of the ice cubes contained therein without first partially melting said cubes.

A further object of the invention is to provide an ice tray grid from which the ice cubes may be removed selectively in multiples of two, either successively or as separate pairs as desired.

A still further object of the invention is to provide an ice tray grid which may be removed from the tray by a wrench or lever and from which the ice cubes may be released by a relative movement of the separate elements of the grid and in which a portion of the grid is used as a fulcrum for the application of power by the wrench or lever both to free the grid and cubes from the tray and to release the cubes from the grid.

Other objects of this invention will appear in the following description and appended claims, reference being had to the accompanying drawings forming a part of this specification wherein like reference characters designate corresponding parts in the several views, and in which:

Fig. 1 is a view in perspective of an ice tray and grid constituting a preferred embodiment of an important part of the present invention.

Fig. 2 is a plan view of a portion of the tray and grid shown in Fig. 1.

Fig. 3 is a longitudinal section taken substantially on the line 3—3 of Fig. 2, looking in the direction of the arrows.

Fig. 4 is a transverse section taken substantially on the line 4—4 of Fig. 3, looking in the direction of the arrows.

Fig. 5 is a view in perspective of the various parts of the grid shown in separated relationship.

Fig. 6 is a view in perspective of an operating member or lever constituting an important part of the present invention, a portion of the lever being cut away.

Fig. 7 is a longitudinal section of one end of the tray and grid shown in Fig. 1, showing the position of the operating member, in folded condition, before the application of power to free the grid and frozen ice cubes from the tray.

Fig. 8 is a sectional view similar to Fig. 7 but showing the position taken by the operating member after power has been applied to loosen the grid from the tray and to release the first two ice cubes, and also showing in dotted lines 10 the position taken by the operating member when applied to separately loosen one of the cross partitions and associated pair of ice cubes.

Fig. 9 is a longitudinal sectional view of the tray and grid showing the position of the various parts of the grid and the operating member when utilized in extended condition, prior to the application of power to loosen the grid or remove the ice cubes.

Fig. 10 is a longitudinal sectional view of the forward or operating end of the tray and grid as shown in Fig. 9, showing the position taken by the grid and operating member after the application of power to remove the grid.

Fig. 11 is a sectional view similar to Fig. 10 25 showing the position taken by the grid and operating member after applying power to remove the ice cubes.

Fig. 12 is a view in perspective of an ice cube after its removal from the tray.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation, and it is not intended to limit the invention claimed herein beyond the requirements of the prior art.

In the embodiment of the invention shown in the drawings, 10 represents an ice tray of the usual size and shape, and 11 represents the grid member, which is constructed to provide a plurality of compartments for forming ice into cubes or any other desired shape within the tray 10. The grid 11 comprises a longitudinal partition 12 and a plurality of transverse partitions 13. Associated with the partitions 12 and 13 in a manner to prevent the separation of the various parts is a slideable bar 14 which extends longitudinally and centrally along the upper portion of the assembled grid. Each transverse partition 13 is 55

provided with a vertical slot 15 extending from its central to its lower edge portion and a vertically extending lug 16 in its upper portion, while the longitudinal partition 12 is cut out at spaced 5 points along its upper edge to provide a series of wide slots or cut-out areas 17 extending from the upper edge of the partition approximately to its mid-point. These cut-out portions are of such shape as to provide a vertical surface rearwardly 10 thereof and a steeply sloping surface forwardly thereof, which permits the transverse partitions positioned therein to be moved from their normal vertical position to a more or less sharp forwardly 15 tilting position. The longitudinal partition 12 is also provided with horizontally and longitudinally 20 extending slots 18 which define lugs 19 thereon and provide a guideway for the bar or plate 14.

During the assembling of the grid the slide bar 20 14, which is provided with suitably shaped slots 20 and 20a, is applied over the lugs 16 and 19, as well as the projection 21 on the partition 12, the function of which will subsequently be described. The ends of the lugs 19 are then slightly bent to 25 either side in order to retain the bar 14 and the various partitions 11 and 12 in assembled relationship. The lugs 16, with the exception of the lug immediately rearward of projection 21, may be omitted, if desired, as they are not essential 30 to the operation of the tray. They render the grid somewhat more compact and unitary, however, and also make it possible to return the cross partitions to their initial position with a single rearward push on the slide bar 14.

35 The projection 21 is provided with a forwardly extending nose 22, the forward and lower edges of which constitute a fulcrum for the removable operating member or lever 23. Although various forms of levers may be utilized in operating the 40 grid of the present invention, a two-part folding lever of the type shown in Figs. 6 to 11 has been found most satisfactory for the stated purpose. This lever comprises a handle member 24 and a dragging or gripping member 25, each of which is 45 provided at one end with a pair of prongs 26 and 27 respectively, adapted to be pivotally connected to each other. The prongs 26 are joined at a point spaced from their pivotal connection with the prongs 27 by means of a cam 28 which is 50 adapted to contact the nose 22 on projection 21, and being offset from the pivotal connection of the handle member 24 causes a constantly increasing forward movement of the gripping member 25 as the handle is raised or rotated 55 about the prongs 27. To facilitate the application of the lever 23 to the grid, the prongs 26 are each provided with notched ends 29.

In operation, the operating member 23 may be 60 folded as shown in Figs. 7 and 8, in which case the action of the cam 28 on nose 22 causes, in addition to the loosening of the entire grid from the tray, which may be held on any suitable supporting surface, a release of the pair of cubes situated adjacent the point of power application in the 65 tray. This selective release of this pair of ice cubes is obtained as a result of the slight forward movement of the slide bar 14 which is produced by pressure of the notched ends 29 of the prongs 26 against the shoulders 30 on the end of the 70 slide bar (see Fig. 5.) As the widened portion 31 of the first slot 20 on bar 14 is the only one which fits snugly about the lug 16 on its associated cross partition, it is apparent that the only cross partition which is affected by movement of 75 the bar 14 is the most forwardly situated one,

and therefore, when using the wrench in the manner described above, the first pair of ice cubes are the only ones released during or immediately following the initial loosening of the grid from the tray. 5

Assuming that it is only desired to remove two cubes of ice, the tray and grid are returned to the refrigerator, and at a subsequent time the wrench may be applied in the manner shown in dotted lines in Fig. 8 to remove another or other 10 pairs of ice cubes, as desired. In this case also the wrench is applied in its folded condition, the prongs 26 and 27 being pressed down against the lug 16 while the cam 28 is pressed upwardly against the forward edge of the adjacent lug 19. 15 Thus, some or all of the ice cubes may be removed in multiples of two by repeatedly applying the wrench in its folded condition in the manner described.

When it is desired to loosen the grid from the 20 tray and release some or all of the ice cubes, i. e., more than two, with one upward movement of the handle member 24, the gripping portion 25 of lever 23 is applied over the various lugs 16 and 19 and the projection 21 in the manner shown 25 in Figs. 9 to 11, and the handle 24 is moved upwardly until the cam 28 strikes the lower edge of the nose 22 as previously described. The tray 10 may be held on any suitable supporting surface, and when the cam 28 first contacts the nose 30 22 the force applied tends to loosen the grid 11 and its contained ice as a unit from the tray, as shown in Fig. 10. The effect of further raising of the handle 24 is shown in Fig. 11. Thus the gripping member 25 of the lever 23 is moved further forward, and during this movement the downwardly extending projections or teeth 32 formed by the notches 33 contact the upper edges of the cross partitions 13 adjacent thereto. In the preferred embodiment of the invention the 40 teeth 32 are spaced progressively farther apart in direct proportion to their distance from the forward end of the lever, as this causes them to progressively contact the various cross partitions 13, beginning with the most forwardly situated one, 45 and thus successively loosen or release the pairs of ice cubes situated forwardly thereof. It should be understood, however, that the teeth 32 may be spaced an even distance apart, although such an arrangement is not as desirable in view 50 of the fact that far greater force is required on the handle 24 in order to simultaneously release the entire content of ice cubes in the tray than where the action is a progressive releasing of successive pairs of ice cubes as above described. 55

In the operation of the lever 23 in the above manner, it is seen that the first partition is tilted forward both by the first pair of teeth 32 on gripping member 25 and by the slide bar 14, while the remaining cross partitions are tilted 60 solely by the teeth 32. It is possible to make the widened portions of slots 20 in bar 14 progressively longer, in which case the bar 14 could be utilized to successively remove the ice cubes and the lever could be used in its folded position 65 for all purposes. An arrangement of this nature is, however, the subject matter of a co-pending application of mine.

When using the lever 23 in its extended position, it is sometimes necessary to hold the rearward end of the gripping portion 25 to prevent it from springing upwardly as a result of the downward force applied at its pivoted end. Any suitable means may be provided to accomplish this, such as a slotted lug on the rear end of the 75

longitudinal partition. In the case of the lever shown in the drawings, however, this is done manually.

A grid of the type described above is readily removable from the tray by means of a simple mechanical lifting action of the lever, and this action may be continued to cause the removal of all or a portion of the ice cubes formed in the grid. Thus a two-fold effect is obtained by means of one continuous application of power. Further, it is possible to remove any number of ice cubes in multiples of two either at one time or at different times during the use of the tray, and the removal of the cubes is greatly facilitated by the progressive movement of the transverse partitions of the grid, since the power applied need merely be directed to a single pair of cubes at a time with the result that less resistance is offered to the removal of the cubes. The grid described herein is also so arranged that the forces applied for releasing the cubes are directed against the central slide bar and are not applied to the walls of the tray or to the ice, as has usually been the case in prior constructions of this nature.

To further facilitate the loosening of the grid and the removal of the ice cubes, particularly the first pair removed, the tray 10 may be provided with a sloping forward wall 34, although it should be understood that the effective operation of the grid is not dependent on a tray of this nature and trays of ordinary shape or construction may readily be used.

It should be observed that this invention is not restricted to a progressive flow of power through the grid or a progressive movement of the cross partitions. Thus the invention described herein may be readily modified in the manner previously suggested to provide an embodiment thereof which is capable of readily dispensing the entire contents of the tray at one and the same time with a single application of power by actuation of the wrench.

In the description herein and in the appended claims reference has been repeatedly made to a forward or rearward position or movement of the various parts of the tray. By "forward" is meant that portion of the tray or grid which is provided with the fulcrum or nose against which force is applied to remove the grid from the tray or release the ice cubes from the grid. The rearward portion of the grid or tray is the opposite end.

I claim:

55 1. In combination with an ice tray, a grid comprising a longitudinal partition and a plurality of movable transverse partitions; and a removable operating member comprising a handle member adapted to contact said longitudinal partition and a shifting member pivoted thereto and slotted at longitudinally spaced points to position said operating member longitudinally of said grid and provided at longitudinally spaced points with projections adapted to contact said transverse partitions, whereby upon moving said operating member said transverse partitions are moved relative to said longitudinal partition.

2. In combination with an ice tray, a grid comprising a longitudinal partition and a plurality of tilttable transverse partitions; and a removable operating member comprising a handle member adapted to contact said longitudinal partition and a dragging member pivoted thereto and provided with progressively spaced projections adapted to contact said transverse parti-

tions, whereby upon moving said operating member said transverse partitions are moved progressively relative to said longitudinal partition thereby to successively release the ice adhering to said transverse partitions. 5

3. In combination with an ice tray, a grid comprising a longitudinal partition, a plurality of transverse partitions tiltably mounted on said longitudinal partition, and a slideable bar connected to said partitions and adapted to be moved to tilt the transverse partition situated adjacent the forward end of said grid; and a removable operating member adapted to move said slideable bar and to contact said transverse partitions to tilt the remainder of said transverse partitions 15 away from their normal position.

4. In combination with an ice tray, a grid comprising a longitudinal partition and a plurality of transverse partitions tiltably mounted on said longitudinal partition, and a removable operating member, said longitudinal partition having an upwardly and outwardly extending projection at one end and said operating member having means for contacting said transverse partitions and a cam surface adapted to contact said projection, whereby as said surface is forced against said projection said transverse partitions are tilted from their normal position. 20 25

5. In combination with an ice tray, a grid comprising a longitudinal partition having a series of lugs extending from its upper edge and an upwardly and outwardly extending projection at one end, and a plurality of transverse partitions each having a lug extending upwardly from its upper edge adjacent one of said lugs on said longitudinal partition; and a removable operating member comprising a drag bar and a handle pivoted thereto, said drag bar having a series of slots adapted to receive the lugs on said partitions and means for successively contacting said transverse 30 35 partitions, and said handle having a cam surface adapted to contact said projection, whereby as said handle is moved upwardly said surface contacts said projection and said drag bar progressively tilts said transverse partitions from their 40 45 normal position.

6. In combination with an ice tray, a grid comprising a longitudinal partition having a series of lugs extending from its upper edge and an upwardly and outwardly extending projection at one end of said upper edge, and a plurality of transverse partitions each having a lug extending upwardly from its upper edge adjacent one of the lugs on said longitudinal partition; and a removable operating member comprising a drag 50 55 bar and a handle pivoted thereto, said drag bar having a series of slots adapted to receive a pair of the lugs on said partitions and having a series of longitudinally spaced teeth adapted to contact the upper edges of said transverse partitions, and said handle having a cam surface adapted to contact said projection, whereby as said handle is moved toward said projection said transverse partitions are tilted from their normal position thereby to successively release the ice adhering 60 65 thereto.

7. In combination with an ice tray, a grid comprising a longitudinal partition having a series of lugs extending from its upper edge and an upwardly and forwardly extending projection at its 70 forward end, a plurality of transverse partitions each having a lug extending upwardly from its upper edge adjacent and at right angles to one of the lugs on said longitudinal partition, and a slideable bar extending longitudinally along the 75

upper surface of said partitions and having a plurality of longitudinally spaced slots each adapted to receive one of the lugs on said longitudinal partition and the lug on one of said transverse partitions; and a removable operating member comprising a drag bar and a handle pivoted thereto, said drag bar having a series of longitudinally spaced teeth adapted to contact the upper edges of said transverse partitions, and said handle having a rearwardly extending projection adapted to contact the forwardly extending projection on said longitudinal partition, whereby as said handle is moved toward said grid said rearwardly extending projection contacts said forwardly extending projection and said transverse partitions are tilted from their normal position thereby to successively release the ice adhering thereto.

8. The combination of an ice tray having a separable pan and grid, said grid comprising a longitudinal partition having a raised cam surface on one end thereof, and a plurality of transverse partitions connected with said longitudinal partition for tilting movement relative thereto, with a removable grid and cube release member comprising a lever adapted to pivot about said raised cam surface on said longitudinal partition as a fulcrum, and a mechanical connector pivotally connected to said lever and extending between said lever and said transverse partitions, whereby pivotal movement of the lever about its fulcrum effects tilting movement of said transverse partitions relative to said longitudinal partition. 5 10 15

CLIFFORD R. CARNEY.
